N. Y., A CORPORATION OF NEW YORK.

APPAREL GARMENT

Application filed June 26, 1928. Serial No 223,489.

This invention relates to an apparel garment and more particularly to a surgical belt or binder adapted to support the abdomen, and also to reduce and confine the thighs and buttocks of the wearer. The garment, however, as herein described, may be so constructed as to be adapted merely to function as a belt and abdominal support.

In carrying out the invention the garment made in accordance therewith is so constructed as to be easily applied and adjusted to the necessary position and tension to perform the functions required of it. To this end the garment is preferably open and adapted to be connected at the side thereof and is provided with devices for adjustment at the back, and is also provided with abdominal uplift or support straps or equivalent devices in the lower front portions thereof and adjustable on the exterior of the garment in order, as will be understood, to facilitate the placing of the garment on the body and the adjustment of the parts of the garment to the desired tension in order to effect the required support. Furthermore, the thigh and buttocks reducing and confining straps when employed are also preferably placed in the lower front portion of the garment and are not adjustable to position. It will be understood that the thigh and buttocks confining and reducing straps are employed in instances where the parts of the body are abnormally developed and require this service while in shorter and less developed figures the use of the belt with the abdominal support only is preferably employed.

In the drawing Figure 1 is a perspective view showing the use of the garment made in accordance with this invention,

Fig. 2 is a front elevation illustrating the garment,

Fig. 3 is a plan looking at the inner side of the garment with the same in a substantially flat position,

Fig. 4 is a view similar to Fig. 2 showing another form of the invention, and

Fig. 5 is a view similar to Fig. 3 illustrating the type of garment as shown in Fig. 4.

Referring to the drawings and particularly to Figs. 1, 2 and 3, the garment made in ac-

cordance with this invention is constructed to include a body adapted to surround the abdominal portion of the body of the wearer as well as the thighs thereof. The body of the garment is preferably composed of a front member, a back member and side members each of which may include several sections. As illustrated, the front member comprises the sections 10, 11, 12 and 13. The section 10 is connected to the section 11 by a reinforcing strip 14 and suitable lines of stitching 15 constructed, as shown, to also enclose a suitable stay 16. The stay 16 extends from the upper edge of the garment downwardly to a point appreciably above the lower edge thereof. This reinforcing strip and stay extend in a central longitudinal position in the front of the garment. The section 10 is connected to the section 12 by a reinforcing strip 17 and lines of stitching 18. As illustrated these may also be made to enclose a stay member 19. In like manner the section 11 is connected to the section 13 by a reinforcing strip 20 and lines of stitching 21 which are made to enclose a stay 22. As illustrated the sections 10 and 11 may also be provided with stays as indicated at 23 and 24. The stay members 19, 22, 23 and 24 extend downwardly from approximately the upper edge of the garment and are appreciably shorter than the stay member 16. The lower edges of the sections 10 and 12 and the sections 11 and 13 of the front member of the garment are cut away as indicated at 25 and 26 providing a centrally disposed depending portion 27.

The right hand side of the garment as illustrated is constructed to include sections 28, 29 and 30. The section 28 is connected to the section 12 by a reinforcing strip 31 and suitable lines of stitching 32. The section 29 is connected to the section 28 by a reinforcing strip 33 and lines of stitching 34. In like manner the section 30 is connected to the section 29 by a reinforcing strip 35 and lines of stitching 36. These parts may also be provided with suitable stays as indicated at 37 and 38 which respectively are associated with the reinforcing strips 33 and 35. The upper portion of the side member is preferably completed by an elastic insert. As illustrated, the

sections 28, 29, and 30 terminate at a line 39 which is appreciably below the upper edge of the garment and the side member is completed by an elastic insert 40, the lower edge of which 5 is connected to the upper edge of the sections of the side member while the forward edge is connected to the section 12 of the front member and the rearward edge is connected to the adjacent section of the back member as hereinafter described.

It will be noted that the reinforcing strips 33 and 35 extend over the elastic insert 40 as do also the upper ends of the stays 37 and 38.

The back member of the garment is preferably composed of divided sections. One of these sections is indicated at 41 and the other at 42. The section 41 is connected to the section 30 by a reinforcing strip 43 and lines of stitching 44 which may be constructed to enclose a stay 45. The opposite edge of this section 41 is reinforced in a suitable manner and provided with stays 46 and 47 between which there is located a series of lacing eyelets 48.

In a similar manner the adjacent edge of the section 42 of the back member is provided with stays 49 and 50 in suitably spaced positions and between which there is a series of lacing eyelets 51 corresponding in number and positions with the eyelets 48. Threaded 25 through the eyelets 48 and 51 there is a connecting and adjusting lace 52.

The opposite or left hand member of the garment as illustrated is constructed to include sections 53, 54 and 55. The section 53 35 of this side member is connected to the adjacent edge of the section 42 of the back member by a reinforcing strip 56 and lines of stitching 57. Enclosed within the reinforcing strip 56 there is a stay 58. The section 53 of this 40 side member is connected to the section 54 by a reinforcing strip 59 and lines of stitching 60 made to enclose a suitable stay 61. Similarly the section 54 is connected to the section 55 by a reinforcing strip 62 and lines of stitching 63 made to enclose a stay 64. The sections 53, 54 and 55 of the left hand side of the garment 45 terminate at their upper edges on a line 65 which is appreciably below the upper edge of the front and back members and like the 50 righthand side member the upper portion of the left hand side member is completed by an elastic insert 66. The upper edges of the sections 53, 54 and 55 are suitably connected to the lower edge of the elastic insert 66 and 55 the rearward edge of the elastic insert is connected to the section 42 of the back member by the same lines of stitching 57 that connect the section 42 to the section 53. The rearward end of the elastic insert 40 is connected to the 60 section 41 of the back member by the same lines of stitching 44 which connect the section 41 to the section 30. At its forward edge the section 55 of the left hand side member is provided with a reinforcing strip 67 which is 65 also connected to the forward edge of the

elastic insert 66 and this reinforcing strip is fitted with a series of suitably spaced eyes 68.

The free edge of the section 13 of the front member is provided with a reinforcing strip 69 connected to which is a series of hooks 70 corresponding in number and positions with the eyes 68 in order that each hook may be caused to engage with its corresponding eye and thereby secure the garment on the body of the wearer.

The garment is also constructed to include uplift straps which are adjustable to position and associated with the front member and placed wholly on the exterior thereof. As clearly shown in Figs. 1 and 2 of the drawing I employ an anchor member 71 which is secured in position at the rearward edge of the section 12 of the front member by the same lines of stitching which connect this section to the section 28 of the adjacent side member. This anchor member 71 may be fitted with a stay 72 and at its free edge is provided with a series of suitably spaced eyelets 73. The right hand portion of the uplift strap also includes an elastic strap 74. At one end 90 this is provided with a reinforcing strip 75 which may be fitted with a stay 76 and is provided with a series of eyelets 77 corresponding in number and position with the eyelets 73. Threaded through the eyelets 73 and 77 is an adjusting lace 78. The opposite or forward edge of the elastic strap 74 is preferably secured in the garment by the same line of stitching which connects the sections 10 and 11 of the front member. In the other side of the garment there is a complementary uplift strap. This includes an anchor member 79 similar to the anchor member 71 and secured at one edge in the garment by the same line of stitching that connects the reinforcing strip 69 to the section 13 of the front member. The anchor member 79 may be provided with a stay 80 and is fitted with a series of spaced eyelets 81. The uplift strap on this side of the garment also includes an elastic strap 82 provided at one end with a reinforcing strip 83 which may be provided with a stay 84 and is fitted with a series of eyelets 85 corresponding in number and position with the eyelets 81.

Threaded through the eyelets 81 and 85 is an adjusting lace 86. The forward edge of the elastic strap 82 is secured or fixed in position in the garment by the same line of stitching which connects the sections 10 and 11 of the front member. These uplift straps are not connected to the sections of the front member except as hereinbefore described and as will be apparent extend from a centrally disposed front position upwardly toward and to the edges of the front member of the garment. Moreover, as will be readily understood in view of the construction these uplift straps are adjustable to position by adjusting 125 130

the laces with which the parts thereof are connected.

In this form of the garment the members of the body thereof are of sufficient length 5 to overlie the thighs and a part at least of the buttocks of the wearer and in the front member there are provided suitable elastic straps 87 and 88 for exerting a tension and placing a corresponding pressure on these parts of 10 the body to confine, control and reduce the same. These straps 87 and 88 are fixed in position in the garment, for example, the forward end of the strap 87, as illustrated, is secured in place by the same lines of stitching 15 that connect the sections 10 and 11 of the front member of the garment while the rear end of this strap 87 is fixed or secured in position by the same lines of stitching that connect the section 12 of the front member 20 to the adjacent section 28 of the right hand side member. In a similar manner the forward end of the elastic strap 88 is fixed in the garment by the lines of stitching which connect the sections 10 and 11 of the front 25 member while the rearward edge of the elastic strap 88 is fixed or secured in the garment by the lines of stitching which connect the section 13 of the front member and the reinforcing strip 69. These elastic straps 87 30 and 88 extend downwardly from the front central longitudinal portion of the front section to the distant edges of the front section as clearly illustrated in Fig. 2 of the drawing.

The uplift straps are so placed in the garment 35 that the lower edges thereof are made to conform with the groin section of the wearer and the upper edges of the cut-away portions of the sections of the front member are substantially coincident with these lower 40 edges of the uplift straps while the upper central portions of the elastic straps 87 and 88 overlie the lower front portions of the uplift straps and the elastic straps 87 and 88 extend across the cut-away portions in the 45 lower parts of the sections of the front member. By this construction, as will be understood, a tension in a circumferential, as well as in an upward direction is effected by the uplift straps to support the abdomen, while 50 a tension in a circumferential and also a slightly downward direction is exerted by the elastic straps 87 and 88, causing the lower portions of the garment to confine and shape the hips of the wearer by a circumferential 55 and slightly upward pull on the same.

Also, as illustrated, the garment may be provided with suitable hose supporters, for example, hose supporters 89 and 90 are attached to the lower edge portion of the front 60 member and hose supporters 92 and 93 are connected to the lower portion of the distant sides of the front member, while the hose supporters 94 and 95 are attached to and depend from the central portions of the side 65 members. The hose supporters, however,

may be placed in any desired positions to adequately support the hose of the wearer.

In some instances where the body is relatively short and the thighs and buttocks are not overdeveloped, the garment in which the present invention is incorporated may be constructed to omit the thigh reducing straps, as illustrated in Figs. 4 and 5. In this form of the invention the body of the garment is relatively shorter but includes members of 70 the same general construction with which the uplift straps are incorporated. 75

In this form of the invention the uplift straps are made in two parts, as in the other form of the invention, and each includes an anchor member and an elastic strap adjustably connected to each other. As illustrated in Fig. 4 the anchor member on the right hand side of the garment is indicated at 98 and the elastic strap associated therewith at 99. 80 These members are provided respectively in the adjacent edges thereof with series of eyelets 100 and 101 through which the adjusting lace 102 is threaded. The anchor strap is connected along one edge in the garment by the lines of stitching which connect the adjacent edges of the front member and the right hand side member, while the forward edge of the elastic strap 99 is connected to the front central portion of the front 85 member by a reinforcing strip 103 and lines of stitching 104. On the left hand side of the garment the complementary anchor member is indicated at 105 and the elastic strap associated therewith at 106. These members 90 are fitted with a series of eyelets 107 and 108 through which an adjusting lace 109 is threaded. The distant edge of the anchor strap 105 is connected to the front member by the reinforcing strip and lines of stitching 100 by which the said reinforcing strip is connected to this edge of the front member and the forward edge of the elastic strap 106 is secured in the garment by the lines of stitching 104 which are employed to connect the 95 reinforcing strip 103 and the adjacent sections of the front member to one another. In this form of the garment the back member is fitted with laces making the same adjustable and the garment is adapted to be connected in position on the body at the side 100 thereof by a suitable series of hooks and eyes in the same manner as hereinbefore described in connection with the other form of the invention. 110

In this type of the garment, however, it 115 may be noted that the elastic inserts 110 and 111 are not coincident circumferentially with the side members of the garment but extend merely across the upper portions of the back 120 sections of the side members. This is clearly shown in Fig. 5. It is also to be noted that the garment is so constructed that the upper edge thereof at the front and back is higher than at the sides in order to cause this up- 125 130

per edge of the garment to more properly conform to the waist line of the wearer inasmuch as when in position for use the garment does not extend above the waist line, being as hereinbefore stated a surgical binder or belt to support the abdomen, or to simultaneously support the abdomen and confine, mold and shape the thighs and buttocks of the wearer. It will also be understood that 10 in both forms of the garment as herein shown and described and in other equivalent forms thereof the parts of the front member of the garment underlying the uplift straps are slightly greater in extent circumferentially 15 than the normal minimum length of the uplift straps in order to provide for the intended functioning of these uplift straps in the use of the garment.

I claim as my invention:

20 1. In a garment of the type described, an undivided front member adapted to overlie the abdomen of the wearer, elastic uplift straps each having its forward end secured in a central position to the said undivided 25 front member extending upwardly therefrom and having its distant edge connected to the corresponding edge of the said undivided front member, means for independently adjusting each uplift strap exteriorly of the undivided front member adjacent the rearward edge thereof, and means for securing the garment on the body of the wearer.

2. In a garment of the type described, an undivided front member adapted to overlie 35 the abdomen of the wearer, side members, a back member, elastic uplift straps each having its forward end secured in a centrally disposed position in the undivided front member and extending upwardly therefrom, 40 anchor straps each connected along one edge in a distant edge of the said undivided front member, means for connecting the rearward edge of each uplift strap to the forward edge of the corresponding anchor strap exteriorly 45 of the undivided front member, and means for securing the garment in position on the body of the wearer.

3. In a garment of the type described, an undivided front member adapted to overlie 50 the abdomen of the wearer, side members, a back member, the said side and back members being adapted to extend over the thighs and buttocks of the wearer, elastic uplift straps each having its forward end secured in a centrally disposed position in the said undivided front member and extending upwardly therefrom with its rearward end connected to the corresponding distant edge of the undivided front member means for adjusting the said 55 uplift straps to position exteriorly of the undivided front member, thigh straps each connected at its forward end in a centrally disposed position in the undivided front member, extending downwardly therefrom and 60 having its rearward end connected to the cor-

responding edge of the said undivided front member, and means for securing the garment in position on the body of the wearer.

4. In a garment of the type described, an undivided front member adapted to overlie 70 the abdomen of the wearer, side members, a back member, the said side and back members being adapted to overlie the thighs and buttocks of the wearer, adjustable uplift straps each having its forward end connected 75 in a centrally disposed position to the said undivided front member and its rearward end to the corresponding edge portion of the said undivided front member, inadjustable elastic thigh straps each having its forward end connected in a centrally disposed position to the said undivided front member, extending downwardly therefrom and having its rearward end connected to the corresponding edge portion of the said undivided front member, 80 the lower edge at the rearward end of each of the uplift straps being substantially at the upper edge of the rearward end of the corresponding thigh strap and the forward portions of the said uplift and thigh straps overlapping each other to an appreciable extent, and means for securing the garment in position on the body of the wearer.

Signed by me this 8th day of June, 1928.
